EXTRACTOR FOR WASHING MACHINES

Peter E. Geldhof and Fred A. Conterman, Syracuse, N. Y., assignors to Easy Washing Machine Corporation, Syracuse, N. Y., a corporation of Delaware

Application November 5, 1931, Serial No. 573,168

12 Claims. (Cl. 100—50)

This invention relates to a new and improved extractor for washing machines.

The usual method of extracting liquid from clothes after they have been washed is either by the use of a wringer in which the clothes are passed between pressure rolls, or by the use of a revolving basket or centrifugal extractor.

The disadvantage of a wringer consists in the fact that it frequently injures the clothes and 10 tears off buttons, hooks and eyes.

There is also the objection that it requires power to operate and further, there is the liability that the operator's hand may become caught between the rolls.

15 Although a centrifugal extractor is a highly effective drier, the basket requires high speed rotation and mechanism must be provided for the purpose which is independent from the washing machine driving mechanism, although certain interconnection may exist.

20 Further, where separate washing and drying compartments are provided side by side, the resultant machine is necessarily expensive to manufacture and requires considerable space.

25 The main object of our invention is to provide a liquid extractor to be used in conjunction with a washing machine which is safe to use, and which can, under no possibility injure the clothes.

Another object is to provide a device of this 30 character which can be suspended on a washing machine vat wholly within the circumference thereof, thus conserving space.

Another object is to provide an apparatus which requires no driving mechanism and no expenditure of power other than that derived from 35 tap water.

Another object is to provide an apparatus which is silent in operation and free from all vibratory or other undesirable movement during 40 operation.

A further object is to provide simple and efficacious means for supplying pressure to the extractor vat for extracting the liquid from the clothes contained therein and to relieve this 45 pressure after the clothes have been dried to the desired degree.

Other objects and advantages relate to the details of form and arrangement of parts, all as will more fully appear from the following description taken in conjunction with the accompanying drawings, in which:—

Figure 1 is a top plan view of our device in position on a washing machine vat.

Figure 2 is a section on line 2—2 of Figure 1.

55 Figure 3 is a section on line 3—3 of Figure 1.

Figure 4 is a section on line 4—4 of Figure 3.

Figure 5 is a section on line 5—5 of Figure 4.

Figure 6 is a section on line 6—6 of Figure 3.

Figure 7 is a vertical section through an ejector valve used with our device, showing the same in 5 position on a faucet.

Figure 8 is a vertical section showing a modified way for connecting the extractor vat to a water tap.

Figure 9 is a top plan view of a modified form 10 of our invention.

Figure 10 is a section on line 10—10 of Figure 9 showing the greater portion of the extractor vat in elevation.

Figure 11 is a section similar to Figure 10 15 showing a modified way for connecting the extractor vat to a water tap.

Figures 12, 13 and 14 are diagrammatic views 20 illustrating respective fluid control systems whereby fluid as water, may be supplied to the extractor vat at a higher degree of pressure than that provided by the source.

Although our invention may be used in combination with various types of washing machines, for the purpose of explaining the invention, we 25 have shown it in combination with a washing machine of the conventional dolly type comprising a vat 1 preferably having its upper edge flaring outwardly and flanged to form an internal shoulder 2. (See Figure 1.)

A dolly 3 is mounted in the vat 1, and may be 30 driven in any conventional way. The means for oscillating the dolly not being a part of this invention, such means has only been indicated generally at 4.

Our extractor comprises an annular trough 5 having an aperture 6 in its bottom. Trough 5 has secured thereto a plurality, in this instance shown as three, of circumferentially spaced legs 7 secured to trough 5 as by bolts 8.

The legs 7 extend outwardly and downwardly from the trough 5 and are adapted to rest on the shoulder 2 on vat 1 to hold the trough 5 suspended over vat 1 and coaxial therewith.

A short distance beneath trough 5 is positioned 45 an annular strap 9 which is secured as by bolts 10 to legs 7 to stabilize such legs, and also to act as a stabilizer for the extractor vat about to be described.

The extractor vat 11, (see Figure 3) has its 50 upper edge rolled outwardly and downwardly, and is inserted through trough 5 and strap 9 and moved downwardly until the rolled upper edge thereof engages the inner wall of the trough 5.

A flexible water impervious bag or clothes con- 55

tainer 12 which conforms generally to the shape, and size of vat 11 is inserted therein with its upper edge rolled outwardly and downwardly, around and engaging the upper edge of the vat 11. The material of which the bag or squeezer 12 is formed preferably has sufficient innate elasticity to tightly grip the vat and normally maintain its relative position.

For reasons stated, the clothes container 12 is preferably made of rubber, but it may, if desired, be made of other appropriate material which is impervious to water.

An annular channeled ring 13 of inverted U-shape in cross section is fitted snugly over the upper edges of clothes container 12 and vat 11 to retain the same in position on the wall of trough 5 and form a base for fluid passageways to be later described.

A circular frame or hood 14 is positioned on the outer wall of trough 5 and is secured thereto as by bolts 16. Frame 14 (see Figure 2) is provided with a plurality of circumferentially spaced ribs 15 which contact with the upper face of ring 13 when the frame 14 is in position on the outer wall of trough 5 to maintain the parts tightly in position, the spaces between the ribs forming fluid discharge passageways leading from squeezer 12 to trough 5.

Frame 14 is secured to trough 5 partially by bolts 16 and partially by the bolts 8 at different points in the periphery thereof.

Frame 14 being bolted to trough 5 with ribs 15 in contact with ring 13, the clothes container 12 and the extractor vat 11 are rigidly secured to trough 5, the entire structure being removable as a unit.

The inner edge of ring 14 is castellated to form a plurality of spaced inwardly extending lugs 17.

40 A bracket 18 has one end hinged to ring 14 and extends inwardly. On the inner end of bracket 18 is rotatably mounted on a headed post 19, coaxial with vat 11, a circular cover 20. (See Figure 3.)

45 Cover 20 is provided on its periphery with a plurality of circumferentially spaced outwardly extending lugs 21 which are adapted to enter the spaces between the lugs 17 on ring 14 and move downwardly to a position beneath said lugs 17.

50 For the purpose of limiting the downward movement of cover 20 in ring 14, we provide on the edge of cover 20 an outwardly extending lug 22 which is adapted to contact with the upper face of ring 14 when the cover is moved to the closed position. On the edge of cover 20, we provide an upwardly extending knob 23 by which cover 20 may be conveniently rotated on its pivot 19.

55 When the cover 20 has been brought to the closed position and it is desired to operate the device, such cover 20 is partially rotated by means of the knob 23, and this partial rotation of the cover 20 will bring the lugs 21 on the cover 20 beneath the lugs 17 on the ring 14 so that the cover 20 will be locked in the closed position.

For the purpose of limiting such movement of the cover 20 so that it will be conveniently brought to rest in either the locked or unlocked position, we provide on bracket 18 opposed bosses 25 and 70 26 with which the finger 24 contacts to limit the rotary movement of the cover 20.

75 Referring to Figures 4 and 5, we provide on the under face of trough 5 a spout 27 swingingly mounted on a headed bolt 28 which is secured to the under face of trough 5.

Spout 27 has an outwardly extending lip 29 by which it is mounted on bolt 28.

We provide adjacent the upper end of bolt 28, a washer 30, and adjacent the lower end thereof and against the head of such bolt, a second 5 washer 31.

A spiral spring 32 encircles bolt 28, and is seated against the opposing washers 30 and 31 to urge trough 27 upwardly into frictional contact with a washer 33 interposed between it and the under 10 surface of trough 5 so that the spout 27 will be frictionally held in an adjusted position.

Spout 27 is so designed that when it is in the position shown in Figure 4, the inner end thereof will be beneath the aperture 6 in the trough 5 15 so that liquid escaping from the trough 5 will enter the spout 27.

When the spout 27 is in this position, it extends outwardly beyond the vat 1 so that any liquid discharged therefrom will be discharged extra- 20 neously of such vat 1.

If it is desired to return the washing fluid extracted from the clothes to the washing vat, the trough 27 is swung about its pivot 28 to bring the inner end of such spout outwardly and out of 25 registration with the aperture 6. This will permit any liquid escaping from the trough 5 to return directly to the vat 1.

For the purpose of operating our device by means of tap water, we provide an injector 30 device 34 having a main body 35 approximately T-shaped.

In one end of body 35 is positioned by a pressed fit a nozzle 36 which extends inwardly a sufficient distance so that when liquid is ejected 35 therefrom, it will tend to pass directly through the body 35 rather than into the laterally extending arm 37.

On the lower end of body 35, we provide a discharge spout 38 secured in position as by a 40 bolt 39 and having adjacent its lower end a cross strap 40.

The lower end of body 35 functions as a seat for a valve 41 which is carried on the end of a rod 42 which is threaded in cross strap 40. 45

On the lower end of rod 42, we provide a handle 43 so that rod 42 may be conveniently rotated to move valve 41 towards and from its seat.

On the upper end of nozzle 36, we provide a rotatable internally threaded collar 44 by means 50 of which the device may be secured in position on a faucet 45.

The arm 37 is connected as by a conduit 46 to a spout 47 secured to the under surface of extractor vat 11 and in communication with the interior thereof. When it is desired to extract liquid from clothes, they are placed in the container 12 and the cover 20 is locked in the closed position. The valve 41 is then seated on the end of body 35 and the faucet 45 is opened. The 60 tap water cannot escape past valve 41 and it therefore flows through conduit 46 and into the extractor vat 11. The water will force the squeezer or flexible bag 12 upwardly to carry the clothes against the under surface of cover 65 20, and as the pressure against the clothes gradually increases, the liquid in the clothes will be forced out of the same, and over the ring 13 between ribs 15 and it will then escape through the ports 48 into the trough 5, and from there it will flow through the aperture 6 either into the spout 70 27 or back into the washer vat 1 depending upon the position of spout 27.

When the liquid has been extracted from the clothes, the valve 41 is opened and the water 75

escaping from the faucet 45 will then pass outwardly past the valve 41 into the sink or laundry tub.

The movement of the water from the nozzle 36 past the arm 37 will cause the water in the extractor vat 11 to be drawn outwardly through the conduit 46 and discharged past the valve 41, and the extractor vat 11 will thus be emptied in preparation for the reception of another batch of clothes.

In Figure 2, we have shown conduit 46 connected to a spout 47 eccentrically positioned in the bottom of extractor vat 11. As a modification of our invention, we have shown in Figure 8 extractor vat 11 secured to the upper end of vertical conduit 49 which extends through a hollow shaft 50 on which the dolly and a portion of its operating mechanism is mounted. In this construction, the conduit 46 is connected to the lower end of the conduit 49. In this embodiment, the extractor vat 11 is provided with an internally threaded boss 51 adapted to engage the threaded upper end of the conduit 49 so that extractor vat 11 may be conveniently placed in position on conduit 49 or removed therefrom.

In Figures 9 and 10, we have shown a structure which is identical in all material respects with the structure shown in Figures 1 to 7 inclusive with the exception that instead of having three similar legs as 7, by which the extractor basket 11 is suspended co-axially with the washer vat 1, we have provided a pair of comparatively long legs 52 together with a comparatively short vertically extending leg 53 so that the extractor basket 11 is suspended eccentrically of the washer vat 1 and adjacent the edge thereof.

In Figure 11, the extractor basket 11 is suspended in the same way as shown in Figure 9, but in this embodiment we provide a conduit 54 similar to the conduit 49 shown in Figure 8 which extends vertically through the dolly supporting means, and which is connected to the bottom of the extractor basket 11 as by an internally threaded rotatable collar 55.

The structure here disclosed is one which is very compact and space-saving in that the extractor is supported on the washer vat wholly within the circumference thereof so that the space required is merely the space required by the washer vat.

It is also an arrangement which is convenient to use in that the extractor may be very easily removed from the washer vat when it is desired to clean the same or if the operator prefers to have the extractor in a different place. In the structure disclosed in Figures 1 to 7, and in Figures 9 and 10, the operator merely has to lift the extractor off from the washer vat. In the structure disclosed in Figures 8 and 11, the extractor basket may be easily disconnected from the feed conduit and then lifted bodily from the tub.

In Figures 12, 13 and 14, we have illustrated various water control systems adapted to increase the pressure of the water in the extractor vat in case the pressure of the water from the source is insufficient to extract the liquid from the clothes contained in the extractor vat to the desired extent.

This system consists of suitable by-passes connected with the supply conduit for the extractor vat composed of pipes or tubing having suitable pumps and control valves connected therewith which are adapted to increase or boost the pressure of the water to the desired degree for extracting the liquid from the clothes contained in

the container 12 in the manner hereinbefore described.

In Figure 12, the extractor vat 11 is connected with the ejector 34 by means of the vertical conduit 49 and a supply conduit 60 which connects the ejector 34 with the conduit 49 in a manner similar to that illustrated in Figure 8, while the ejector 34 is illustrated as being secured to the faucet 45 for supplying water to the ejector vat 11 or for emptying the vat of said water after the completion of the extracting process in the manner similar to that shown in Figure 2.

The supply conduit 60, in this instance, is provided with a check valve 61 intermediate its ends and which is adapted to permit the water 15 to flow therethrough in one direction only: that is, from the ejector to the extractor vat. A supply by-pass conduit 62 is connected with the supply conduit 60 at opposite sides of the check valve. This by-pass conduit 62 is provided with 20 a suitable pressure pump 63 which, in this instance, is represented as a gear pump adapted to draw the water from the ejector and to force the same into the extractor vat 11 and may be operated from any suitable source of power such, for 25 instance, as the mechanism for operating the dolly 3 in the washer vat 1 and which is not necessary to herein illustrate or describe as it does not constitute any part of this invention.

In order that the pressure in the vat 11 will 30 not become excessive when the pump is operated, a relief conduit 64 is connected with the supply by-pass conduit 62 at opposite sides of the pressure pump 63 and this relief conduit has secured therein a suitable relief valve 65 adapted to open 35 at a pre-determined pressure to permit water to be re-circulated through the pump. A second conduit 66 having a control valve 67 operably connected therein, is also connected with the supply conduit 60 at opposite sides of the check 40 valve 61 to form a return passage for the water valve 61 to form a return passage for the water when it is desired to empty the vat 11 after the liquid has been extracted from the clothes.

In operation, the ejector valve is closed by the manipulation of the handle 43 in the manner 45 previously described, and with the control valve 67 in the closed position, the faucet 45 may be opened after which the water will pass from the ejector 34 into the supply conduit 60 and through the check valve 61 into the extractor vat 11. 50

The water will force the squeezer or flexible bag 12 upwardly to carry the clothes against the upper surface of the cover 20, and if the pressure is insufficient to extract the desired amount of liquid from the clothes, this pressure may be 55 increased by setting the pressure pump 63 into operation which will draw the water from the supply conduit 60 at the inlet side of the check valve 61 and return it to the supply conduit 60 at the outlet side of said check valve thereby closing 60 the check valve which will cause the water to be forced into the vat 11 under gradually increasing pressure until the pressure in the vat has been increased sufficiently to extract the liquid 65 from the clothes to the desired extent after which the operation of the pressure pump 63 may be discontinued, and when desired, the water may be withdrawn from the extractor vat 11 by opening the return control valve 67 and the ejector 70 valve after which the water escaping from the faucet 45 will then pass outwardly through the ejector in the manner previously described, which will cause the water in the extractor vat 11 to be drawn outwardly through the conduit 60, return 75

conduit 66 past the control valve 67 into the conduit 60 and thence to the ejector 34.

In Figure 13, there is shown a device similarly constructed to that illustrated in Figure 12, except that the return conduit 66 is not provided with the control valve 67 and that the supply by-pass conduit 62 is provided with an extension 62' which also connects with the supply conduit 60 intermediate the inlet of the conduit 60 and the connection of said conduit 60 with the conduit 62 which, in this instance, is at the junction of the conduit 60 and the return conduit 66 at which point a suitable straight valve 69 is positioned, as illustrated.

This valve 69 is adapted to permit the water coming from the source to flow straight through the conduit 60, as illustrated in the drawings, or may be turned at right angles to the position shown for connecting the return conduit 66 with the conduit 62'. Furthermore, the supply by-pass conduit 62 is connected at the outlet side of the pump 63 with an outlet conduit 70 which may, as shown, be provided with a suitable nozzle or spout 71 for directing the discharge water, as desired, as will presently be more fully explained.

At the junction of the outlet conduit 70 and the supply by-pass 62 is positioned a two-way valve 72 adapted to direct the water through the conduit 62 or from the conduit 62 into the outlet conduit 70.

In this instance, the source of water supply may come from the faucet 45 or from a suitable storage tank as 73. If the water is to be taken from the tap, the inlet end of the conduit 60 may be connected with the faucet 45, as illustrated by full lines, and if the water is to be taken from the storage tank 73, the inlet end of the conduit 60 may be extended into said tank, as illustrated by dotted lines. In either instance, when supplying the vat 11 with water, the valve 69 may be positioned, as illustrated in the drawings, directly connecting the conduit 62 with the inlet of the conduit 60 whereupon the pump 63 will draw the water from the source and force it through the two-way valve 72 which is positioned, as illustrated, to permit the flow of water through the conduit 62 and thence through the outlet end of the conduit 60 and conduit 49 into the vat 11 in the manner previously described for the construction shown in Figure 12.

When it is desired to empty the vat 11, the valve 69 may be turned at right angles to the position illustrated in the drawings, connecting the return by-pass 66 with the conduit 62' and the valve 72 may be turned to connect the conduit 62 with the outlet conduit 70, whereupon the pump 63 will then draw the water from the vat 11 through the conduit 49, the adjacent end of the conduit 60 and thence through the by-pass conduit 66, valve 69 and conduit 62' to the conduit 62, thence through the pump 63, conduit 62 and through the valve 72 to the conduit 70 and thence out through the spout 71.

This discharge water may be returned to the storage tank 73 if desired, as indicated by dotted lines, or may be discharged as otherwise desired, such as into the washer vat 1 or into the sewer.

In Figure 14 is illustrated a still further modified form of control system in which the supply conduit 60 may be connected with the faucet 45 or storage tank 73 in the manner illustrated and described for the device shown in Figure 13. In this instance, however, the outlet conduit as 70 is provided with a volume pump 75 which is adapted to discharge the water at a much greater

speed than when the pressure pump 63 is utilized and for this reason, the valve 72 is adapted to connect the vat 11 with the outlet conduit 70 without the necessity of the water passing through the pressure pump 63, and in order that the washer vat 1 may also be emptied by this same pump, we have shown a discharge conduit as 76 connected with the valve 72 at right angles to the outlet conduit 70 and which is connected with the vat 1 by means of a spout 77.

When it is desired to extract the liquid from the clothes contained in the extractor bag 12, the valve 72 may be positioned as illustrated in Figure 14 for permitting the water to pass through the conduit 62 after which the water may be drawn by the pump 63 from the faucet 45 or storage tank 73 in the manner described for the device shown in Figure 13 and forced upwardly into the vat 11, and when it is desired to draw the water from the vat 11 after extracting the liquid from the clothes, the valve 72 may be turned to connect the conduit 62 with the outlet conduit 70 at which time the pressure pump 63 may be discontinued and the volume pump 75 set into operation to draw the water from the vat 11 and discharge as desired, in the manner described for the device shown in Figure 13.

In the device shown in Figure 14, the pressure pump 63 may also be utilized to supply the washer vat 1 with water, in which case the valve 72 may be turned to connect the conduit 62 with the conduit 76 connected with the vat 1 at which time, it is obvious, the operation of the pump 63 will draw the water from the source of supply and force it through the valve 72 and conduit 76 into the vat 1.

Likewise, the water contained in the vat 1 may be drained therefrom by the volume pump 75 by turning the valve 72 to connect the conduit 76 with the outlet conduit 70.

Although we have shown and described a specific structure and form and relation of the parts thereof, as an exemplification of an embodiment of our invention, we do not desire to restrict ourselves to the exact size, shape and relation of parts, as various changes may be made within the scope of the appended claims.

We claim:

1. In a device of the class described, an annular trough having a discharge outlet, an extractor vat, a flexible container inside of the vat, means for securing the upper edges of the vat and the container directly and rigidly to the trough, means for introducing liquid under pressure into the vat beneath the container and means for supporting the trough on the vat of a washing machine.

2. In a device of the class described, an annular trough having a discharge opening, a vat having its upper end rolled outwardly and in engagement with the inner edge of the trough, a flexible container in the vat having its upper end rolled outwardly and in engagement with the rolled upper end of the vat, an annular ring embracing the rolled ends of the vat and the container, a frame secured to the outer edge of the trough and being in engagement with the upper face of the ring, a cover for the vat carried on the frame, and means for introducing liquid under pressure into the vat beneath the flexible container.

3. In an extractor for drying clothes, an extractor vat having a flexible container therein, a trough for receiving the liquid extracted from the clothes, means for suspending said extractor

vat from said trough, a frame member secured to said trough and means on said frame member for securing said extractor vat rigidly to said trough.

5. In an extractor for drying clothes, an extractor vat having a flexible container therein, a trough for receiving the liquid extracted from the clothes, said extractor vat depending from said trough, a frame member secured to said trough and ribs extending from said frame member for securing said extractor vat and said flexible container to said trough.

5. In an extractor for drying clothes, an extractor vat having a flexible container therein, a trough for receiving the liquid extracted from the clothes, said extractor vat depending from said trough, an annular frame member having means thereon for retaining said extractor vat rigidly in position, a hinged member on said frame, and a rotatable cover depending from said hinged member and engaging said frame.

6. In a device of the class described in combination, an annular member having a trough-shaped portion adapted to receive water extracted from the clothes, an extractor vat carried by and suspended from said trough, means therein for extracting water from clothes, a clothes washing vat, and means for supporting the trough together with the extractor vat from the rim of the washer vat.

7. In a device of the class described in combination, an extractor vat, means therein for extracting water from clothes, an annular member positioned adjacent and around the upper circumference of the extractor vat, a cover for the extractor vat hinged to said annular member, means for suspending the extractor vat from the annular member, a clothes washing vat, and means extending therefrom to said annular member for supporting the extractor vat wholly from the washer vat.

8. In a device of the class described in combination, an extractor vat, means therein for extracting water from clothes, an annular member positioned adjacent and around the upper circumference of the extractor vat and from which the extractor vat is suspended, means extending from said annular member for holding said extractor vat rigidly in position, a clothes washing vat, and supporting members extending inwardly from the rim of the washer vat circumferentially thereof for supporting said annular member and said extractor vat from the washer vat.

9. The combination with a washing vat for washing clothes, of an extractor comprising an extractor vat having a flexible container therein, a trough for receiving the liquid extracted from the clothes, means for suspending said extractor vat from said trough, a frame member secured to said trough, means on said frame member for securing said extractor vat rigidly to said trough, means for supporting said trough wholly from the rim of said washing vat and a drain member pivotally supported beneath said trough enabling the liquid extracted from the clothes to be conveyed to an external vessel or to be carried to said washing vat.

10. In an apparatus of the class described, a squeezer for extracting water from clothes comprising a cup-shaped container and a ring-like member seated thereon and secured thereto, a flexible bag within the container having its free edge tightly confined between the upper edge of the cup-shaped member and the ring, a trough surrounding the upper end of the container for receiving fluid therefrom, and a cover separate from said ring member adapted to overlie said container.

11. In a device of the class described, an annular trough having a discharge opening, a vat having its upper end rolled outwardly and in engagement with the inner edge of the trough, a flexible container in the vat and having its upper end rolled outwardly and in engagement with the rolled upper end of the vat, an annular ring embracing the rolled ends of the vat and the container, a frame secured to the outer edge of the trough, means on said frame engaging said annular ring to hold said vat rigidly in position, a cover for the vat carried on the frame, and means for introducing liquid under pressure into the vat beneath the flexible container.

12. In a laundering apparatus, the combination of a trough and an extractor vat depending from and supported by said trough, a flexible container, means for suspending said flexible container from the upper edge of the vat, and means for introducing fluid under pressure beneath said flexible container to express fluid from the clothes and cause it to flow over the upper edge of said flexible container and into said trough.

PETER E. GELDHOF.
FRED A. CONTERMAN.
